COLLAPSIBLE LUGGAGE CARRIER

Filed June 2, 1948

UNITED STATES PATENT OFFICE

2,469,242

COLLAPSIBLE LUGGAGE CARRIER

Elsa Pohl, New York, N. Y.

Application June 2, 1948, Serial No. 30,592

4 Claims. (Cl. 280—36)

1

My invention relates to carriers or carriages for suitcases or similar pieces of luggage.

Objects of my invention are to provide such a carrier with collapsible parts whereby the dimensions of the carrier can be considerably reduced when not used, to provide a collapsible carrier which can be easily stored in a suitcase or can be conveniently carried by any person without burdening the same appreciably, and to provide a collapsed carrier that can be easily and quickly put into condition of use whereby a traveling person can move his suitcases and bags easily at any desired time.

Other objects are a collapsible luggage carrier that can stand and move like a carriage and that forms a stable support of the carried things throughout its use, a luggage carrier that can be pulled by a handle positioned about at the level of a person's hand whereby the movement of the carrier is convenient, to connect this handle to the platform of the carrier by a shaft whereby the carrier forms a coherent unit which is independent from the carried luggage, to provide this shaft with a hinge pin which allows turning movement of the shaft with respect to the platform when the carrier is in condition for use whereby the direction of the shaft and the height of the handle can be adjusted as desired and convenient, and to conceal the shaft under the platform when the carrier is not used.

Further objects are to provide the carrier with a platform adapted for carrying pieces of luggage of different sizes, to provide the carrier's platform with an adjustable extension plate, and to shift this plate substantially completely into the platform when the carrier is not used.

Still further objects are to obtain these results with simple and reliable means and with a structure that can be easily and inexpensively made, and that can be easily handled, collapsed and adjusted for use.

Still other objects and advantages will appear from the following description of an exemplifying embodiment of my invention, from the appended claims and from the accompanying drawing in which:

Fig. 1 shows a partially sectional side view of an illustrative embodiment of my invention in collapsed condition, the sectionally represented part being cut along the line 1—1 in Fig. 2.

Fig. 2 shows a partially sectional bottom view of the same embodiment, the cross-section being taken along the broken line 2—2 in Fig. 3.

Fig. 3 shows a cross-section taken along the line 3—3 in Fig. 1.

2

Fig. 4 shows a perspective view of the same embodiment in condition of use, a suitcase carried by this embodiment being indicated by dotted lines. Fig. 4 is represented on a smaller scale than Figs. 1 to 3.

Referring to the drawing, numeral 4 indicates a rectangular platform, and 5 wheels supporting this platform. There are more than two, preferably four, wheels 5 which are so distributed that these wheels form a stable support of the platform and of the luggage carried by the latter. For example, the wheels are positioned near the four corners of the platform. Preferably the wheels are casters of well known type. These casters adjust their direction to any moving direction, each wheel being rotatable in a bracket 6 which can turn around a vertical axis relatively to a disk 7 affixed to the lower side of the platform 4.

20 A casing 8 is positioned under the platform 4 and so affixed to the latter that the casing and the platform form one piece. The casing has an elongated shape and preferably extends through the length of the platform 4. The cross-section of the casing and of its inner space may be rectangular. The casing comprises a bottom 9 and two lateral walls 11. The ceiling of the casing may be formed by the platform 4. The walls 11 extend to the front of the carrier a little beyond the platform 4. The inner space of the casing forms a straight channel of uniform cross-section and is open at the front side. The rear end of the channel also may be open. Each of the lateral walls 11 has a longitudinal slot 12 which is closed at both ends.

25 A shaft part 13 comprises two parallel elongated arms or tongues 14 which are connected at their rear ends whereby the part 13 has a forked shape. Two co-axial pins 15 of cylindrical shape are affixed to the part 13 near its rear end and project horizontally into the slots 12 whereby the part 13 can slide in the direction of these slots as far as the slots allow and, in the foremost position, can turn around the axis of the pins 15. The part 13 fits the inner space of the casing 8.

30 Another shaft part 16 has an elongated shape fitting the space between the arms 14 and is so connected to the part 13 that these parts can slide relatively to each other in their longitudinal directions. Preferably the arms 14 have longitudinal slots 17, and the part 16 is provided with horizontally extending pins 18 reaching into the slots 17. There may be two pairs of pins 18 positioned at a suitable distance from each other.

The position of the foremost pins 18 determines the end of the relative shiftability of the shaft parts so that some portions of the parts overlap in any position. A handle 19 is affixed to the front end of the part 16.

The parts 13 and 16 together form a shaft which, in the condition of use shown in Fig. 4, has a considerable length larger than the length of the platform 4 and sufficiently large to raise the handle 19 up to the level of the hand of a pulling person. In collapsed condition, the combined shaft fits the inner space of the casing 4 and can be concealed within this casing as shown in Figs. 1 to 3. In condition of use, the part 13 forms the rear and lower part of the shaft, and the part 16 forms the front and higher part of the shaft.

The upper side of the platform 4 is provided with a broad groove 21 which extends in longitudinal direction of the platform from the latter's rear end over a considerable portion of the platform's length. The groove 21 has dove-tailed sides. A plate 22 of correspondingly dove-tailed cross-section fits the groove 21 slidably. In the position shown in Fig. 4, the plate 22 is partly shifted out of the groove 21 and forms an extension of the platform 4 whereby the carrier is adjusted for carrying a suitcase 23 which is longer than the unextended platform 4. The width of the platform is about equal to the usual width of a suitcase of this length and is considerably smaller than the usual height of such a suitcase.

The rear end of the plate 22 may be provided with an upwardly projecting end plate 24 which stops rearward shift of the suitcase 23. Preferably, the end plate 24 is hinged to the plate 22 whereby the end plate can be folded down as shown in Figs. 1 to 3. For example, projections 25 are affixed to the rear end of the plate 22 and enter recesses of the end plate 24, and a hinge pin 26 connects the end plate and the projections 25 rotatably. In the raised position of the end plate 24 shown in Fig. 4, the lower end of the end plate contacts the rear end of the plate 22 whereby the end plate is prevented from turning farther to the rear side.

The total height of the carrier in the collapsed condition shown in Figs. 1 to 3, or the heights of the platform 4 and the end plate 24 over the ground are considerably smaller than the usual width of the suitcase 23 whereby the collapsed carrier has a very small size and can be easily placed within the suitcase 23 when the carrier is not used; the carrier having three dimensions perpendicular to each other each of which is smaller than one of three perpendicular dimensions of the suitcase.

In order to adjust the carrier for use, the handle 19 is pulled to the front whereby first the shaft part 16, then also the shaft part 13 slides out of the casing 8 until the pins 15 prevent further extraction. Then the shaft may be turned up around the axis of the pins 15. The plate 22 is shifted to the rear as far as the size of the suitcase to be carried requires, and the end plate 24 is turned up.

Means may be provided to secure the shaft parts and the plate 22 in the thus adjusted positions. For example, the shaft may be secured by a wedge or bolt 27 inserted in a suitably positioned opening 28 of the shaft part 16 whereby this shaft part is prevented from sliding back into the shaft part 13. If the carrier shall be not only pulled but also occasionally pushed, the position of the pins 15 may be secured by inserting a bolt or

wedge 29 tightly in one or both slots 12 immediately behind the pins 15. The plate 22 may be secured by means of winged screw bolts 31 which pass through threaded holes of the platform 4.

5 When these screw bolts are tightened, they press the dove-tailed sides of the plate 22 and of the groove 21 together.

I desire it understood that my invention is not confined to the particular embodiment shown and described, the same being merely illustrative, and that my invention may be carried out in other ways without departing from the spirit of my invention as it is obvious that the particular embodiment shown and described is only one of the many that may be employed to attain the objects of my invention.

Having described the nature of my invention, what I claim and desire to protect by Letters Patent is:

20 1. A luggage carrier comprising a platform, wheels supporting said platform in a substantially horizontal position, a casing affixed to the lower side of said platform, extending along substantially the entire length of said platform and having a wall with a longitudinal slot, said casing being open at its front end, said slot being closed at the front end, a shaft fitting the inner space of said casing slidably, a pin affixed to said shaft near the rear end of the same and reaching into 25 said slot, and a handle affixed to the front end of said shaft, said pin forming a hinge of said shaft when the latter is in its foremost position, the front end of said casing and the rear end of said shaft having shapes allowing, in said position, turning movement of said shaft relatively to said casing.

2. A luggage carrier comprising a platform, wheels supporting said platform in a substantially horizontal position, a casing affixed to the lower side of said platform, extending along substantially the entire length of said platform and having a wall with a longitudinal slot, said casing being open at its front end, said slot being closed at the front end, a shaft having a front and a rear part engaging each other slidably in longitudinal direction whereby said shaft can collapse and has a reduced length in collapsed condition, said shaft, in collapsed condition, fitting the inner space of said casing slidably, a pin affixed to said rear part near the rear end of the same and reaching into said slot, and a handle affixed to the front end of said front part, said pin forming a hinge of said shaft when the latter is in its foremost position, the front end of said casing and the rear end of said shaft having shapes allowing, in said position, turning movement of said shaft relatively to said casing.

3. A luggage carrier comprising a platform, wheels supporting said platform, a casing affixed to the lower side of said platform, extending along substantially the entire length of said platform and having a wall with a longitudinal slot, said casing being open at its front end, said slot being closed at the front end, a plate engaging said platform slidably in longitudinal direction and shiftable from a position where said plate forms a rear continuation of said platform to a position where said plate and said platform are collapsed, a shaft fitting the inner space of said casing slidably, a pin affixed to said shaft near the rear end of the same and reaching into said slot, and a handle affixed to the front end of said shaft.

4. A luggage carrier comprising a platform, wheels supporting said platform, a casing affixed

to the lower side of said platform, extending along substantially the entire length of said platform and having a wall with a longitudinal slot, said casing being open at its front end, said slot being closed at the front end, a plate engaging said platform slidably in longitudinal direction and shiftable from a position where said plate forms a rear continuation of said platform to a position where said plate and said platform are collapsed, a shaft having a front and a rear part engaging each other slidably in longitudinal direction whereby said shaft can collapse and has a reduced length in collapsed condition, said shaft, in collapsed condition, fitting the inner space of said casing slidably, a pin affixed to said rear part near the rear end of the same and reaching into said slot, and a handle affixed to the front end of said front part, said carrier, when said

10

shaft is collapsed and shifted into said casing and when said plate and platform are collapsed, having a length smaller than the length of suitcase adapted to be supported by said platform and said plate in not collapsed condition, having a width smaller than the usual height of such a suitcase and having a height smaller than the usual width of such a suitcase.
